United States Patent Office

Des. 181,818
Patented Dec. 31, 1957

181,818

MOBILE

Francis A. Sly, Arlington, Va.

Application February 5, 1957, Serial No. 44,761

Term of patent 14 years

(Cl. D29—1)

Fig. 1 is a front elevational view of a mobile, showing my new design;

Fig. 2 is an end elevational view;

Fig. 3 is a top plan view; and

Fig. 4 is a front elevational view showing the movable elements in another position.

The characteristic feature of my design resides in the portion thereof located above the tripod.

I claim:

The ornamental design for a mobile, as shown and described.
